UNITED STATES PATENT OFFICE.

FRANK H. HINKLEY, OF ERIE, AND HARRY E. JOHNSON, OF KANE, PENNSYLVANIA.

MEANS FOR LUBRICATING JOURNAL-BOXES.

1,070,257.

Specification of Letters Patent.

Patented Aug. 12, 1913.

Application filed April 23, 1912. Serial No. 692,723.

To all whom it may concern:

Be it known that we, FRANK H. HINKLEY and HARRY E. JOHNSON, citizens of the United States, residing at Erie and Kane, respectively, in the counties of Erie and McKean and State of Pennsylvania, have invented certain new and useful Improvements in Means for Lubricating Journal-Boxes, of which the following is a specification.

The invention relates to improvements in means for lubricating journal boxes.

The object of the present invention is to improve the construction of means for lubricating journal boxes, and to provide a simple, efficient and comparatively inexpensive construction, designed particularly for use on the driving boxes of a locomotive, and capable of lubricating the journal and hub of an axle and the shoes and wedge of a driving box and of affording increased strength and durability to the latter by enabling the top of the driving box and the cellar to be made solid where recesses are ordinarily provided for the reception of lubricant holding sponge or waste.

With these and other objects in view, the invention consists in the construction and novel combination of parts hereinafter fully described, illustrated in the accompanying drawings, and pointed out in the claims hereto appended; it being understood that various changes in the form, proportion, size and minor details of construction, within the scope of the claims, may be resorted to without departing from the spirit or sacrificing any of the advantages of the invention.

In the drawings:—Figure 1 is a front elevation of a lubricator, constructed in accordance with this invention and shown applied to a locomotive driving box, the journal being in section. Fig. 2 is a vertical transverse sectional view of the same. Fig. 3 is a horizontal sectional view on the line 3—3 of Fig. 2. Fig. 4 is a longitudinal sectional view of the driving box. Fig. 5 is a side elevation of the same. Fig. 6 is a horizontal sectional view on the line 6—6 of Fig. 4. Fig. 7 is a detail perspective view of the adjustable wedge.

Like numerals of reference designate corresponding parts in all the figures of the drawings.

In the accompanying drawings in which is illustrated the preferred embodiment of the invention, 1 designates a locomotive

driving box, provided at opposite sides with vertical flanges 2 and arranged in the opening 3 between the sides 4 of the pedestal portion of the frame 5 of a locomotive, and rigidly secured in the said opening by means of shoes 6 and 7 and a wedge 8, which operates with an inclined inner face 9 of one of the sides of the pedestal portion of the frame in the usual manner. The shoes are 65 of the ordinary flanged construction to embrace the pedestal portion of the frame, and the wedge is adjusted by means of a vertical bolt or screw 10, mounted in a threaded opening of the pedestal brace 11 and provided above and below the same with nuts 12 and 13, the head of the screw 10 being seated in an opening 14 of the wedge, which is provided with a recess 15, located at the bottom of the opening for the said screw 10. 70 The upper nut engages the lower edge of the wedge, and the screw is provided with a lower squared end 16 to enable it to be adjusted by means of a wrench, said screw being locked in its adjustment by the lower 75 nut 13, which engages the lower face of the pedestal brace. The ends of the pedestal brace are secured to the bottom of the frame at opposite sides of the pedestal by bolts 17.

The driving box receives a crown brass 18 85 in the upper portion of its opening and a cellar 19 within the lower portion of the said opening, the crown brass being arranged upon the upper edges of the sides of the cellar and adapted to rest upon the journal 20 in the usual manner, as clearly illustrated in Figs. 1 and 2 of the drawings. The inner face 21 of the cellar is spaced from the journal a slight distance, preferably about the eighth of an inch, to prevent friction, and the lower side edges of the crown brass are cut away or beveled at the inner face at 22 to avoid shoulders for preventing the crown brass from scraping the lubricant from the journal. The driving box is provided at the lower portion of its back with a flange 23, disposed in a vertical plane and presenting a curved inner edge to the journal arranged substantially concentric with the same.

The back of the driving box fits against the hub of a wheel (not shown) and is closed by the same. The cellar is rendered dust proof at the front by means of a flexible or elastic gasket 24 of felt, or other suitable material seated in a recess 25 in the cellar and secured to the same by an attaching plate 26

pierced at intervals by screws 27, which also pass through the gasket 24 and engage threaded holes or sockets 28 in the cellar. The felt gasket 24, which is approximately 5 semi-circular, extends around the lower half of the journal and the recess 25 is also approximately semicircular to conform to the configuration of the gasket. The attaching plate is substantially semi-circular and is of 10 a width less than the gasket, which projects upwardly or inwardly beyond the attaching plate, the latter being spaced from the plane of the journal. The upper portions of the side walls 25^a of the recess 25 are vertical, 15 and the outer edges of the gasket and the attaching plate have vertical portions to fit the ends of the recess. The cellar is secured within the lower portion of the opening of the driving box by means of a front horizontal bolt 30, arranged in the usual manner. The driving box is provided at the bottom 20 of its front portion with a recess 31, and the cellar has depending lugs 32 extending into the recess 31 and fitting against the end 25 walls of the same and pierced by the bolt 30, which also extends through the sides of the driving box at the bottom thereof, as clearly shown in Fig. 1 of the drawings.

The crown brass is provided in its inner bearing face with a longitudinal groove 33, and it has an elongated opening 34 in the top wall of the groove 33 to maintain itself constantly in register with an inclined lubricant passage 35, extending through the upper portion of the driving box from the front thereof. The lubricant passage 35 is of a less diameter than the elongated opening and the latter prevents any longitudinal movement of the crown brass from choking the lubricant passage 35 and interfering with the free passage of the lubricant to the groove 33. The lubricant passage 35 is enlarged and threaded at the outer portion to receive a reduced tubular portion or stem 40 36 of a grease cup 37, equipped with a threaded plunger 38 and adapted to operate in the usual manner to force a hard oil or grease lubricant into the driving box. By employing a lubricant passage, the top portion 45 of the driving box between the grooves or recesses 39 may be made solid where a lubricant recess is usually provided for the reception of an absorbent material and the lubricant. Also the lubricating device enables a solid cellar to be employed, and the 50 construction of the driving box may be materially increased in strength and durability by employing such lubricating means.

The crown brass is provided at the inner 55 or rear end of the longitudinal groove 33 with a relatively small groove or recess 40, adapted to feed the lubricant to the hub of the wheel for lubricating the same simultaneously with the journal. In order to prevent the shoes and the wedge from stick-

ing when it is desirable to remove the driving box, the crown brass is provided with transverse lubricant passages 41, extending laterally from the side walls of the longitudinal groove 33 and registering with transverse passages 42 of the driving box. The 60 passages 42 extend outwardly from the lateral passages 41 of the crown brass through the side portions of the driving box to the side faces thereof and communicate with the upper ends of downwardly diverging 65 grooves 43, formed in the side faces of the driving box and located between the side flanges 2 thereof and terminating short of the bottom of the driving box, as clearly 70 illustrated in Fig. 5 of the drawings. The shoe 7, which is interposed between the wedge and the driving box, is provided with a perforation 44 registering with the outer 75 end of the adjacent laterally extending lubricant passage of the driving box and adapted to permit a quantity of lubricant to flow outwardly to the adjustable wedge. In the operation of the lubricator, the lubricant 80 will rise in the longitudinal groove 33 and will flow laterally through the registering lubricant passages of the crown brass, the driving box and the wedge 7 and will lubricate the shoes and the wedge and prevent the same from sticking. This will enable the 85 driving box to be readily removed when desired.

The spaced top grooves 39 are adapted to receive central enlargements 45 of equalizer bars or levers 46, which are connected with 90 springs 47 by hangers 48 in the usual manner.

The inclined lubricant passage 35 is illustrated in the drawings at the front of the driving box, and the grease cup extends upwardly and outwardly from the top portion of the said box, but the lubricant passage may be located at any other convenient portion of the top of the driving box, so as to be clear of the movable parts of the locomotive, and the lubricator is also applicable to the engine and trailer trucks, the side grooves being then unnecessary as the journal boxes of those trucks are not equipped with shoes and wedges.

What is claimed is:—

1. A device of the class described including a journal box provided above its opening with a central solid top portion and having a lubricant passage extending 105 through its top portion to the said opening, said journal box being also provided with transverse passages extending from the opening to the side faces of the journal box, a crown brass located within the upper portion of the opening of the journal box and provided in its bearing face with a central longitudinal groove and having an opening 110 in the top wall thereof to communicate with the said passages and provided with trans-

- verse passages extending from the longitudinal groove to the inner ends of the first-mentioned transverse passages and registering with the same, a solid oil cellar arranged 5 within the lower portion of the opening of the journal box, and a grease cup mounted on the journal box at the outer end of said lubricant passage.
2. A device of the class described includ- 10 ing a locomotive driving box having an inclined lubricant passage in its upper portion and provided at opposite sides with lubricant passages extending from the opening of the driving box to the side faces thereof, 15 the latter being provided with grooves diverging downwardly from the side passages, shoes arranged at opposite sides of the driving box, one of the shoes being provided with a perforation registering with one of 20 said side passages, a wedge fitted against the shoe having the said perforation, a crown brass provided in its inner bearing face with a groove and having an opening to register with the inclined lubricant pas- 25 sage and provided also with side passages extending from the groove and communicating with the side passages of the driving box.

3. A device of the class described includ- 30 ing a journal box provided at the lower portion of its opening with a rear flange, a cellar secured within the lower portion of the opening of the journal box and fitting against the flange and provided in its front face with an approximately semi- 35 circular recess, a yieldable gasket of substantially semi-circular form arranged in the said recess and presenting an inner curved edge to the journal to render the journal box dust proof, an approximately semi-circular 40 attaching plate arranged in the recess, the inner edge of the gasket being extended inwardly beyond the inner edge of the attaching plate, fastening devices piercing the attaching plate and the gasket and securing 45 the same to the oil cellar, a crown brass arranged within the upper portion of the journal box, and means for supplying the latter with a lubricant.

In testimony whereof we affix our signatures in presence of two witnesses.
